UNITED STATES PATENT OFFICE

2,453,971

COMBINED PIPE STAND AND CONTAINER
FOR SMOKING TOBACCO

Raymond Chemlinski, Schenectady, N. Y.

Application June 7, 1946, Serial No. 675,165

2 Claims. (Cl. 131—260)

1

The purpose of my improvement is to provide a tin container for tobacco, especially pipe tobacco, which container is made in a manner to provide a supporting rest for a smoking pipe when the same is not in use.

The object of my invention is to devise an implement of utmost simplicity so as not to appreciably increase the cost of the container in which tobacco is sold to individual users. This I have accomplished in a novel manner without adding any parts to the conventional container, but simply by impressing its surface with raised ridges of definite shape and dimensions, as will be described with reference to the accompanying drawings, in which.

Fig. 1 is a perspective view of a tin container incorporating my improvements;

Fig. 2 is a sectional view of my improved container on line 2—2 of Fig. 1;

Fig. 3 is a sectional view of my said container on line 3—3 of Fig. 1;

Fig. 4 is a perspective view of my container with a differently shaped ridge formation thereon.

Similar numerals refer to similar parts throughout the several views.

The tobacco container 10 shown in the drawings, is made in the conventional form out of sheet metal and is provided with a hinged lid 11. One of the broad surfaces 12 of the container is impressed with a V-shaped ridge 13, the constricted end 14 of the V formation being turned towards the bottom portion of the container, while the arms 15 of said V-formation are open towards the opposite end of the container. The ridge as shown, rises but slightly over the rest of said surface 12 although, if desirable it may be made somewhat higher without materially changing the appearance of the article as a whole. In some cases again it may be desirable to depress the area within the arms of the ridge, thus effectively adding to their height with relation to the depressed surface between said arms.

At the other end of said surface 12, are two short ribs disposed parallel to each other and straddling the bisector of the angle formed by the arms of the V-ridge.

The ribs are made by raising the surface of the container from inside.

Another species of my improved container is

2

shown in Fig. 4 wherein the V-shaped ridge is substituted by a ridge 18 which is semi-circular in shape. The ribs 19, disposed at the opposite end of the container on its upper surface 23, have lateral extensions 20 tapering into the surface till they have blended with it.

Both in the case of my container shown in Fig. 1 and that shown in Fig. 4, the ridge serves as a convenient prop for the bowl of a smoking pipe.

10 Such a pipe is shown in dotted lines 21. The stem 22 of the pipe fits between the ribs 16 or 19 as the case may be.

15 It will be obvious that some changes may be made in the shape of the ridge, the depth of the surface within its area and so on, without deviating from the inventive principle of my improvement disclosed herein.

What I therefore wish to claim, is as follows:

20 1. In a flat tin pocket container for smoking tobacco, a V-shaped ridge on a broad surface thereof, of dimensions to embrace the lower portion of the bowl of a pipe, and a pair of ribs rising on said surface, parallel to, and straddling the bisector of the angle of said V-formation for 25 abutment with the stem of the pipe from opposite sides.

2. In a pocket tin container for smoking tobacco and having a flat surface, a V-shaped ridge on said surface, wide enough to embrace the 30 bottom portion of the bowl of a smoking pipe, and a pair of straight ribs on said surface, to embrace the stem of the pipe, the ribs being spaced from the V-ridge and being alined with the bisector of the angle formed by the arms of said V-ridge.

RAYMOND CHEMLINSKI.
